C. E. BAILEY

WHEELED TOY

Filed Aug. 30, 1922

FIG. 2.

FIG. 3.

13 INVENTOR
13" C. E. Bailey

Frank L. Hinman,
ATTORNEY

UNITED STATES PATENT OFFICE.

CLIFFORD E. BAILEY, OF CROMWELL, CONNECTICUT, ASSIGNOR TO WILLIAM M. SHEEDY, OF MIDDLETOWN, CONNECTICUT.

WHEELED TOY.

Application filed August 30, 1922. Serial No. 585,198.

To all whom it may concern:

Be it known that CLIFFORD E. BAILEY, citizen of the United States, residing at Cromwell, in the county of Middlesex and 5 State of Connecticut, has invented certain new and useful Improvements in Wheeled Toys, of which the following is a specification.

This invention relates to wheeled toys, 10 among the objects of the invention being the provision of an article of this character which is simple in construction and by which energy can be effectively created therein, for impelling the toy over a floor or 15 other support.

In the drawing accompanying and forming part of the present specification, I have shown in detail a form of embodiment of the invention which to enable those skilled 20 in the art to practice the same will be set forth fully in the following description. Clearly I am not restricted to such disclosure. I may depart therefrom in a number 25 of particulars within the scope of the invention defined by the claims following said description.

Referring to said drawing:

Fig. 1 is a side elevation of a toy involving the invention.

30 Fig. 2 is an elevation as seen from the left in Fig. 1.

Fig. 3 is a cross section on the line 3—3 of Fig. 1, looking toward the right.

Like characters refer to like parts 35 throughout the several views.

The toy involves in its construction a body portion which is desirably though not essentially wheeled, and which can be made to represent any object or objects. As 40 shown, the body appearing is denoted in a general way by 2 and it comprises what is intended to simulate or represent a cart 3 in the shafts of which is a dog or other animal 4, the cart being occupied by a clown 45 or other figure 5. These portions of the body 2, that is, the cart 3, the animal 4, and the clown 5 are generally made in one piece from flat stock and can be of metal, wood or composition as desired.

50 As shown, the cart 3 is equipped at the rear of its vertical center with two transversely aligned bearings 6 through which extends the axle 7, furnished with ground wheels 8. These wheels or equivalents when 55 present, are intended to support the toy on

the floor or other surface on which is generally mounted the fore portion of the animal 4.

The body 2 has as shown therein the slot 9 of virtually inverted T-form, this slot as 60 illustrated being formed in the cart portion 3 practically centrally of the length thereof. At one side of the stem or upper portion of the slot 9 and on one side of the cart portion 3, is a lateral bearing or lug 10. Below the 65 central portion of the transverse part of the slot 9 and on the opposite side of the cart 3 is a practically similar bearing 11, these bearings rotatively receiving the spindle 12 which stands diagonally or at angle to the 70 vertical and lies in the slot 9.

That part of the spindle 12 which extends below the bearing 11 is furnished with a foot as 13 practically in the form of a flat disk, which stands at a slight angle and the 75 peripheral portion thereof engages the floor upon which the toy is intended to travel. The spindle 12 near the upper end thereof has through it a perforation or hole 14 which is intended to receive the free end 80 of a proper length of cord or string. The spindle 12 has fixed to it a wheel 13' which stands at an angle to the horizontal.

The action is as follows:

A piece of cord or string will be passed 85 through the hole 14 and the cord will then be tightly wound upon the spindle 12 between the wheel 8 and the upper bearing 10, the toy usually being held free from the floor or other support while this is done. 90 When the cord is pulled at its outer end, the spindle 12 and weighted wheel 13' rapidly rotated so that when the toy is placed upon the floor, the disk or foot 13 by rotating 95 against the floor will propel the toy along the floor.

To facilitate the movement of the toy along the floor or equivalent, it may be equipped with a wheel 4' on the fore leg 100 of the animal 4 or like part. I may also face the disk or wheel 13 with rubber or leather 13'' which also facilitates the action.

What I claim is:

1. A toy comprising a body portion having a slot, the body portion being furnished with 105 bearings on opposite sides thereof, a spindle standing at an upright angle through said slot and rotatively supported by the bearings, the spindle having a weighted wheel 110 rigid therewith and also having a cord re-

ceiving opening between the weighted wheel and the upper portion of the slot, the lower end of the spindle being furnished with a disk that is adapted to rest on the support for the toy.

2. A toy comprising a body portion having a slot, a spindle standing at an angle through said slot, the body portion being provided with means to rotatively support the spindle, the latter having a weighted wheel rigid therewith, and also having means by which a cord can be wound thereon, the lower end of the spindle being furnished with a disk that is adapted to rest directly upon the support for the toy.

3. A toy comprising a body portion hav-

ing a slot, an upright spindle standing at an angle through the slot, the body portion having means to rotatively support the spindle, the spindle having a weighted wheel rigid therewith, the lower end of the spindle being furnished with a disk that is adapted to rest on the support for the toy, and wheeled means for supporting the body portion.

In testimony whereof I hereby affix my signature.

CLIFFORD E. BAILEY.
